United States Patent

Des. 241,794
Patented Oct. 12, 1976

241,794

SOFA OR SIMILAR ARTICLE

Robert L. Jaycox, Chicago, Ill., assignor to Kroehler Mfg. Co., Naperville, Ill.

Filed May 16, 1975, Ser. No. 578,351

Term of patent 14 years

Int. Cl. D6—01

U.S. Cl. D6—63

FIG. 1 is a front perspective view of a sofa or similar article showing my new design.

FIG. 2 is a side perspective view thereof; and

FIG. 3 is a side elevational view thereof.

The side of my sofa or similar article opposite that shown in the figures is symmetrically reverse but otherwise identical.

I claim:

The ornamental design for a sofa or similar article, as shown and described.
